UNITED STATES PATENT OFFICE

ALBERT SABATH, OF CHICAGO, ILLINOIS, ASSIGNOR TO SCENE-IN-ACTION CORPORATION, OF CHICAGO, ILLINOIS, A CORPORATION OF ILLINOIS

TRANSPARENCY

Application filed October 18, 1928. Serial No. 313,293.

This invention relates to transparencies and incense burners and particularly to an illuminating device comprising both transparency and smoke producing incense burner features. The main objects of this invention are to provide a decorative novelty device of the character referred to; to provide an illuminating transparency adapted to accommodate the burning of incense; to provide a 5 fancifully decorated transparency adapted for animated motion effects designed to harmonize illusively with the issuance of real smoke from the device; and to provide such a transparency adapted to express the illusion of smoldering fire, and smoke arising therefrom, in combination with an appropriately disposed smoke generator arranged to discharge its visible fumes in complementary visible harmony with the simulated smoke 10 and apparently continuous therewith.

An illustrative embodiment of this invention is shown by the accompanying drawings in which:

Figure 1 is a front elevation of a complete 25 transparency and incense burner.

Fig. 2 is an enlarged vertical axial section through the device of Fig. 1, on the line 2—2.

Fig. 3 is a perspective view of the incense burner plate which is shown in section in the 30 upper part of Fig. 2.

In the construction shown in the drawings, the device 1 comprises a base 2, a cylindrical housing wall part 3, a top or roofing part 4, a source of light 5, a transparency rotor 6, 35 a transparency screen 7 interposed between said wall 3 and said rotor 6 and a horizontal burner plate 8.

The base 2 is decoratively formed as indicated in Fig. 1 and is provided with supporting legs or feet 9 mutually spaced apart with air spaces 10 interposed to admit air as hereinafter explained. Said base 2 is substantially dome shaped and is provided with a plurality of perforations 11 adapted to serve 40 as air passageways surrounding the central apex where the lamp base or socket 12 is mounted. Electric current is supplied to the lamp 5 through a two conductor cord 13, one conductor 14 of which leads directly to 45 the socket 12. The other conductor 15 leads

to the switch 16 from which a conductor 17 leads to the other side of socket 12. A handle 18 is provided on said switch for turning the current on and off.

The wall member 1 comprises a cylinder 55 of glass, the outer face of which is artistically decorated in transparency fashion by any appropriate means as, for instance, an outer layer of paper 19 adhesively applied and having the desired design already printed thereon. In this instance, the design is reproduced in horizontal alinement on two or more parts of the decorative sheet in order that the pictorial effect may be visible from various directions as will be apparent from 60 Figure 1.

The rotor 20 is formed cylindrically and is disposed concentrically about the lamp 5 as shown in Fig. 2. It is provided with a form retaining hoop 21 adjacent to its lower 65 edge and a cylindrically rimmed fan 22 is secured to and disposed across its upper end where it serves by action of the ascending currents of lamp heated air to drive the rotor clockwise as viewed from the top. Rotation 70 is accommodated by provision of a downwardly facing axial bearing cup 23 on said fan which is thus supported pivotally on the upright member 24 secured at its lower end to the base 2 adjacent to the lamp socket 12. 75

The rotor wall 20 is made of substantially transparent material as, for instance, celluloid or mica and is significantly marked or lined with opague or nearly opaque material as at 80 25 to help express the desired animated motion feature. The lines 25 may be variously formed or inclined on different parts of the rotor in accordance with the effect desired on corresponding parts of the pictured outer wall part 19.

The intermediate screen 26 is also composed of substantially transparent material held in shape by hoop members 27 and 28 and is variously lined or decorated as at 29 to correspond with the adjacently disposed pictured parts on the front member 19. In this instance the greater part of screen 26 is covered with an opaque or nearly opaque coating and the lines 29 represent transparent light transmitting parts to correspond with 85 90 95

and enhance the smoke effect appearing on the permanently decorated face of the part 19.

The burner plate 8 comprises a substantially flat bottom part 30 surrounded by a shallow upstanding rim 31 bordered by an 5 outstanding flange 32 adapted to rest upon the top edge of the wall part 3. The central part is depressed at 33 to provide a receptacle for the combustible incense material where 10 the actual smoke is generated. Surrounding the part 33 are holes 34 to accommodate the upward movement of lamp heated air which escapes through the holes 35 in the roof part 4, carrying with it columns of smoke 36 from 15 the fire part 33. When the device is in use the actual smoke 36 rises in alinement with the simulated smoke 37 on the face of member 19 which, due to the animated motion effect produced by the rotor 6 and screen 7 appears 20 to be actually rising from the lap of the pictured Buddha 38. I regard the device as a lamp specialty, and in view of the effect produced I call it a Buddha lamp.

Although but one specific embodiment of 25 this invention is herein shown and described, it is to be understood that numerous details of the construction shown may be altered or omitted without departing from the spirit of the invention as defined by the following 30 claims.

I claim:

1. A device of the character described comprising a pictorially decorated transparency 35 part of cylindrical shape adapted and arranged to pictorially simulate ascending smoke, and a burner part mounted in the upper portion of said transparency part and being adapted and arranged to discharge real smoke substantially in alinement with the simulated smoke, said parts having draft 40 passageways formed therein.

2. A device of the character described comprising a base, a source of light and heat mounted thereon, animated motion transparency means surrounding said source and 45 mounted on said base, and a burner and a top mounted over said source and carried by said means, said base, burner and top having draft and smoke passages, and said means being 50 decoratively designed to represent pictorially the discharge of smoke from a pictured source and in complementary relation to the real smoke.

Signed at Chicago this 6th day of June,
55 1928.

ALBERT SABATH.
